UNITED STATES PATENT OFFICE.

HENRY EGGERS, OF DENVER, COLORADO, ASSIGNOR TO THE SAMSON MANUFACTURING COMPANY, OF DENVER, COLORADO, A CORPORATION OF COLORADO.

CRUSHER FOR ORE AND OTHER MATERIALS.

No. 893,713.

Specification of Letters Patent.

Patented July 21, 1908.

Application filed September 16, 1907. Serial No. 393,040.

To all whom it may concern:

Be it known that I, HENRY EGGERS, a citizen of the United States of America, residing in the city and county of Denver and State 5 of Colorado, have invented a new and useful Crusher for Ore and other Materials, of which the following is a specification.

My invention relates to improvements in crushers for ores, rock, and other material, 10 and the objects of my invention are: First, to provide an adjustable swinging jaw locking device for ore and rock crusher. Second, to provide a quick releasing device for the stationary jaw supporting frames of ore and 15 rock crushers. And third, to provide an improved form of ore and rock crusher in which the stationary jaw and its supporting frame can be swung up over the top of the crusher's frame, so that both the swinging 20 jaw and the stationary jaw are in full view and can be cleaned, removed, and replaced by new ones, and in which the swinging jaw can be adjustably positioned relative to the 25 stationary jaw, and can be instantly released from its adjusted locked position. I attain these objects by the mechanism illustrated in the accompanying drawings, in which:

Figure 1, is a plan view of my improved ore and rock crusher. Fig. 2, is a longitudinal sectional view of the same. Fig. 3, is an end elevation of the feed end of the crusher. Fig. 4, is a perspective view of the frame to the stationary jaw. Fig. 5, is a perspective view of the locking sleeve. Fig. 35 6, is a perspective view of a cross link, and in connection with the locking mechanism. And Fig. 7, is a side elevation on a reduced scale of the main frame of the crusher.

Similar letters of reference refer to similar 40 parts throughout the several views.

Referring to the drawings, the numeral 1, designates the main frame of my crusher, which is preferably cast in one piece and comprises sides 2, which are connected at the 45 rear by an end member 3, which is of less height than the sides, and a bed plate 4. Journal bearings 5, are formed in the upper ends of the side members, and a shaft 5^a passes through these bearings, and extends 50 beyond them far enough to receive a belt fly wheel 6, which is secured on one end, and a crank handle wheel 7, which is secured on the other end. The central portion of this shaft is provided with an eccentric portion 8, 55 which extends along the shaft between the

sides, and upon the eccentric portion of this shaft I hang a swinging jaw supporting frame 9, at its upper end. This frame hangs from this shaft down between the sides of the main frame to near the lower edge of the 60 frame, at a slight rearward angle of inclination to the vertical plane of the axial center of the eccentric shaft, assuming the closed end of the frame to be its rear end. This swinging frame is provided at its lower end 65 with a rearwardly projecting portion 10, in the end of which a transverse recess 11, is formed, which has a downward inclination from its open side. In the bottom of this recess a pin 12 is seated, the ends of which extend through slots 13, formed in the opposite sides of the frame, and to the ends of this pin I secure one end of a pair of tie bars 14, which are provided with an eye portion at their ends that fits loosely over the ends of 70 the pin 12, in grooves formed in the pin close to its ends to receive the eye portion of the links. The opposite ends of these tie bars are threaded and extend loosely through apertures formed in the ends of a cross link 15, 75 which extends across the lower end portion of the feed side of the frame, and clamping nuts 16 are threaded to the ends of the tie bars and screw against the cross link, the nuts being provided with operating handles, 80 as shown. The central portion of this cross link is round, and upon it I mount an eccentric sleeve 17, which is provided with a recess 18, that extends along the sleeve from end to end, and into it to the axial center of the 85 sleeve, the bottom of which is curved, as shown. This recess incloses the round portion of the cross link, and its curved bottom portion fits against the round surface of the bar, while the eccentric body of the sleeve 90 fits rotatably in a semi-circular recess 19 formed in the adjacent end of a frame 20, which supports the stationary crushing jaw, as will presently be shown. To this eccentric sleeve I secure one end of a hand grasping loop-shaped handle 21, the loop hand grasping portion of which projects upwardly from the eccentric sleeve and normally rests against the end of the frame 20. The inside 100 face of the stationary frame 20, is formed to receive a steel ore or rock breaking jaw 22, and the stationary frame and the steel jaw are inwardly inclined from the top of the frame towards the lower end of the swinging jaw-supporting frame, but at a greater angle 105 110

of inclination to a vertical plane than the swinging jaw frame, in order to form a wedge-shaped space between the two that is wider at the top than at the bottom, and which is 5 adapted to receive the ore or rock to be crushed. The frame 20 comprises an end member, and side members having journal bearings 20^A through which the ends of the shaft 5^A project, and support the same. The 10 sides of the frame, at their lower ends, lie in recesses formed by the sides 2, of the main frame, and uprights 2^A, which form an integral part of the sides 2, but are far enough away from the said sides to permit the side 15 members of the frame 20 to lie between them and rest against the shoulder 2^B, which connects the uprights 2^A with the sides 2 of the main frame.

The front side of the swinging frame 9, is 20 also provided with a removable steel ore or rock crushing jaw 23, which is removably secured to it in any suitable manner, preferably by being formed with a beveled lower end, which is engaged by a beveled lip at the 25 bottom of the swinging frame, and by a bolt 24 at the top of the jaw and frame, that extend through both jaw and frame and clamp the two together. A buffer device is also arranged between the swinging frame and 30 the rear end of the crusher frame. This buffer may consist of any suitable resilient device properly arranged to receive the resilient thrust of the jaw frame, but I preferably carry out this feature of my invention in the 35 following manner: Upon the rear side of the swinging jaw frame, I form a pair of lugs 25, between which I pivotally secure by a pin 26 one end of a buffer rod 27; the opposite end of this rod rests loosely in and extends 40 through an open slot 28 formed in the top of the rear end 3 of the crusher frame, which only extends up high enough between the sides of the crusher frame to form a support for this rod. The free end of this buffer rod 45 is threaded, and a nut 29 is threaded to it. Washers 30 are also mounted on the rod on the inside of the nut, and between these washers, one of which rests against the end of the frame, I mount on the rod a rubber spring 50 sleeve 31, which is adjusted for tension by the nut, as the tightening of the nut against the rubber draws on the rod and lower end of the swinging arm, and which bears against the pin and causes it to pull on the tie rods 55 and cross link, which presses the eccentric sleeve into its semi-circular bearing in the fixed end of the frame 20, which acts as an abutment; consequently the tightening of the buffer rod nut holds the lower end of the 60 swinging arm under a pulling pressure on the tie rods, and eccentric sleeve, against its abutment, and thus holds the lower end of the swinging jaw frame in an adjustable fixed position against accidental horizontal 65 movement from it relative to the stationary

jaw, but at the same time free to move in a rotary swinging plane towards and in operative ore and rock breaking relation to said fixed jaw. Removable wear plates 32, are placed between the sides of the frame 20 and the jaws to prevent the material that passes through the crusher from contacting with the frame 20. These wear plates have V-shaped edges, which fit in correspondingly-shaped recesses, in the sides 2, and in the end of the 75 frame 20.

The operation of the crusher and of its adjustable swinging jaw and quick releasing lock, is as follows: The eccentric shaft may be rotated by a belt applied to the fly wheel 80 pulley or by hand as desired, and as it rotates, its eccentric portion imparts a rotary swinging and oscillatory and reciprocatory movement to the swinging frame relative to the stationary jaw of the crusher. This oscillatory reciprocal movement of the swinging frame is much greater at its upper end than it is at the lower end, as the swinging frame is pivotally supported at its lower end on the pin 12, and the eccentric movement of 85 the top of the swinging frame is consequently converted into a slight vertically-inclined oscillating or rocking movement of the lower end of the rock arm on the tie rods 14. The lower end of the swinging frame 90 can be adjustably set at any desired position relative to the stationary jaw, so as to regulate the size of crushed product by manipulating the tie rods 14, and buffer rod 27, and in case at any time it is desired to look at the 100 crushing jaws, the eccentric sleeve is removed from the cross link 15 by grasping its loop handle and swinging it down in the direction of the arrow, which turns the eccentric portion of the sleeve out of its semi-circular bearing in the end of the frame 20, and allows the cross bar and tie rods to drop down below the end of the frame, when the 105 said frame and its jaw can be swung up over the top of the main frame in the direction of the arrow 33, with its jaw facing out, while the swinging frame and jaw 9, are exposed to full view from the forward end of the machine.

My invention is simple, durable, and practical, and enables the jaws to be examined at any time without stopping the movement of the eccentric driving shaft and swinging frame.

Having described my invention, what I 120 claim as new and desire to secure by Letters Patent, is:

In an ore and rock crusher, the combination with the main frame, of the crusher frame, having a stationary jaw; an oscillating jaw arranged in operative relation to said stationary jaw, a recess in said swinging jaw, a pin journaled in said recess, a pair of tie bars positioned one on each side of said frame, provided with eyes at one end fitting 125 130

loosely over the opposite ends of said pin, and having their opposite ends threaded, an abutment bearing adjacent to said stationary jaw in said crusher frame, a rotatable tie 5 bars loosening and tightening eccentric abutment sleeve mounted in said abutment bearing, and provided with an open slot portion in its side, a link in said side slot extending across said frame, eye portions on the opposite ends of said link fitting loosely over the threaded end portions of said tie rods, and a handled nut threaded to the threaded ends of each rod and arranged to screw against the

eye portions of said link and clamp it and its eccentric sleeve to the abutment bearing of 15 said frame, and means including a handle connected to said eccentric sleeve for rotating it to instantly loosen said tie rods and release said jaw from its set positions relative to said fixed jaw. 20

In testimony whereof I affix my signature in presence of two witnesses.

HENRY EGGERS.
